UNITED STATES PATENT OFFICE.

PLATO G. EMERY, OF CHICAGO, ILLINOIS, ASSIGNOR, BY MESNE ASSIGNMENTS, TO THE CURTAIN SUPPLY COMPANY, OF SAME PLACE.

CURTAIN-FIXTURE.

SPECIFICATION forming part of Letters Patent No. 636,128, dated October 31, 1899.

Application filed December 22, 1898. Serial No. 700,036. (No model.)

To all whom it may concern:

Be it known that I, PLATO G. EMERY, of Chicago, in the county of Cook and State of Illinois, have invented certain new and useful 5 Improvements in Window or Curtain Fixtures, of which the following is a specification, reference being had to the accompanying drawings and to the numerals of reference marked thereon.

10 My invention relates more especially to such window or curtain fixtures as are designed for use in railway-cars, and are of that description in which the curtain may be raised or lowered to any height within the limit of the frame, with its cross-bar or stick always parallel with the top and base of the frame, and remain at any height to which it may be moved.

15 The object of the present invention is to obtain simple and effective means whereby the curtain-stick, however rapidly or suddenly it may be moved, cannot be tilted out of its horizontal position or thrown from the confining-frame.

20 In the use of other devices intended to accomplish similar results it has been found that by taking the curtain-stick near one of its ends and giving it a quick jerk that end or the stick at both ends is liable to be thrown 25 from the frame. In railroad practice curtains of this class are frequently subjected to violent and unskilful manipulation by passengers, and unless the curtain-stick is kept within the grooves of the frame by positive 30 means much inconvenience from such disarrangement is liable to occur.

To simplify, cheapen, and render more effective such curtain-fixtures, especially in the respects mentioned, is the object of my 40 invention.

In the accompanying drawings, Figure 1 is a face view or elevation of a window-frame provided with a curtain-fixture constructed in accordance with my invention and in position, the frame or casing being shown in section. Fig. 2 is a vertical longitudinal section of the frame on the line 2 2 of Fig. 1, showing the invention applied. Fig. 3 is a transverse section on the line 3 3 of the same figure. Fig. 4 is an enlarged view, mainly in longitudinal section, showing the main fea-

tures of the invention. Fig. 5 is a transverse section on the line 5 5 of Fig. 4. Fig. 6 is a perspective view of a detail. Fig. 7 is an end view of the same detail. Fig. 8 is a section 55 on the line 8 8 of Fig. 4. Figs. 9, 10, 11, and 12 illustrate modifications of details of the invention.

Similar numerals of reference indicate similar parts in the several figures. 60

1 is the window-frame, and 2 the curtain, which may be of any suitable design or construction. The curtain 2 is of fiber, leather, or other material and is here shown wound upon a spring-roller 3, which at all times has 65 the tendency to wind the curtain up on the roller, and thus raise the curtain to its highest position. The bottom of the curtain is provided with a loop or cylindrical pocket 4, within which is slipped a continuous tube 70 5, carrying operative parts hereinafter described.

Each side of the frame 1 is provided with a groove, at the bottom of which is placed a rack 6 of any desired construction. As here 75 shown, the racks 6 consist of perforated strips of metal, so that their outer surfaces are flat. At each end of the continuous tube 5 is telescopically placed a sleeve 7, each sleeve having at its outer end a cylinder 8, provided 80 with a cover-plate 9^a, furnished with wings 10, the wings resting in depressions 11 in the edge of the cylinder, one of the wings being bent over its circumference and fastened thereto by a screw 12. Secured to one side 85 of each cylinder and preferably forming a part of the cover-plate is an elongated shoe or yoke 13, having upon a pivot centrally of its length a cog-wheel 14, adapted to engage with a rack 6 at its side of the frame. In 90 each end of the shoe (the same construction obtaining at each end of the curtain-stick) is mounted a roller 15, the peripheries of the rollers being adapted to rest upon the flat face of the rack. 95

Within each of the cylinders 8 is a cog 9, which engages or meshes with the cog 14. The cog-wheels 9 are each mounted upon a tube 16, each one fitting within a sleeve 7 and being surrounded by a spiral spring 18, one 100 end of each spring fitting against the shoulder 7^a of a sleeve 7, while the other abuts against

a collar 17, loosely fitting around the divided and lapped ends of the tubes 16. It will be understood that the tubes 16 are independent of each other, a separation or slip-joint being made, as seen in Figs. 4, 10, and 11, the two latter figures showing modifications, herein-after described, of this feature of the invention. The tendency of the spiral springs 18 is to keep in engagement the cogs 9 and 14 at the ends of the curtain-stick and also to force the cogs 14 into engagement with the racks 6 and the grooved rollers 15 against the faces of the racks. A continuous rod 19 passes through the two tubes 16, one end of the rod being provided with a head 19^a, which fits against a shoulder 16^a in that tube, (shown at the right-hand side of Fig. 4,) while the opposite end of the continuous rod 19 is provided with a thread having thereon a nut 20, which when screwed up forces a washer 21 against the face of the cog 9 at its end of the curtain-stick. The function of the continuous rod 19 is to tie the two separated and lapped tubes 16 together under the proper conditions, although, as will appear hereinafter, it is not essential to the invention.

One form of slip-joint formed at the meeting ends of the separated tubes 16 is indicated in Figs. 4 and 5, while other forms are shown in Figs. 10 and 11. In Fig. 10 the right-hand tube 16 is furnished with a squared projection 16^b, which fits into a similarly-shaped hole 16^c of the other tube, while in Fig. 11 each of the separated tubes is furnished with a squared hole 16^c, a central connecting-piece 16^e being provided, having at each end a projection 16^b, as in Fig. 10. In these modifications a continuous rod 19 is not needed. Other means of connection will readily suggest themselves to the skilled mechanician.

The function of the elongated shoes 13 is to prevent binding on the sides of the grooves in the frame on account of the offset rendered necessary by the right-angled gearing. The rollers 15, which may be grooved or not, are intended to serve as bumpers to reduce noise incident to the meshing of the cogs 14 with the racks 6.

In Fig. 9 a modified form of gearing is shown, forming the connection between the rack-gears 14 and the tube 16.

In operation the cogs 14 are forced into engagement with the racks 6, the rollers 15 resting on the racks, and as the curtain-stick is moved up or down revolution is imparted to the cogs 14, which travel in the racks 6. The engagement of the cogs 14 with the cogs 9 causes the rotation of the tubes 16 in the sleeves 7. The outward thrust of the springs 18 causes the inner faces of the cogs 9 to bear against the faces of the cylinders 8, thus producing a certain amount of friction. At the same time friction is produced between the outer surfaces of the tubes 16 and the inner walls of the sleeves 7. There is also a certain

amount of friction between the gears 9 and 14, between the cogs 14 and the racks 6, and between the rollers 15 and the faces of the racks, the sum of the friction being sufficient to counteract the upward pull of the curtain-spring, so that the curtain is held at any point within the limits of the frame to which it may be pulled or pushed.

It is obvious that minor changes not involving invention may be made in the construction of the several parts. Thus the mode of attaching the cover-plates 9^a to the cylinders 8 may be modified, as also may the mode of attaching the elongated shoes 13 to the cylinders.

It has been found in practical use that this device overcomes objections heretofore found to exist in fixtures intended for a similar purpose. It is equally applicable to closed cars, open street-cars, or to other adaptations of spring-actuated curtains.

In using the word "curtain" I wish also to include a flexible screen, a slatted blind, a spring-actuated window-sash, or other equivalent device.

Instead of using rollers 15 on the ends of the shoes 13 I may substitute therefor springs, such as shown at 15^a in Fig. 12.

Having thus described my invention, what I claim is—

1. In a curtain-fixture, the combination of a spring-actuated curtain, a curtain-stick, a shoe at each end of the curtain-stick, a cog carried by each shoe, a roller at each end of each shoe, racks with which said cogs engage and against which said rollers bear, and means for retarding the rotation of the cogs, substantially as set forth.

2. In a curtain-fixture, the combination of a spring-actuated curtain, a curtain-stick, a shoe at each end of the curtain-stick, a cog carried by each shoe, a roller at each end of each shoe, racks with which said cogs engage and against which the rollers bear, means for thrusting the cogs and rollers into engagement and contact with the racks, and means for retarding the rotation of the cogs, substantially as set forth.

3. In a curtain-fixture, the combination of a spring-actuated curtain, a curtain-stick, cogs carried by the curtain-stick on axes concentric therewith, cogs meshing with said axially-journalized cogs and also carried by the curtain-sticks, racks with which said last-mentioned cogs engage, means for thrusting the cogs into engagement with the racks, and means for retarding the rotation of the cogs, substantially as set forth.

4. In a curtain-fixture, the combination of a spring-actuated curtain, a hollow curtain-stick, a cog at each end of the curtain-stick journaled in the axial line thereof, cogs also carried by the curtain-stick and journaled at a right angle to said first-named cogs, racks with which said second cogs engage, means for thrusting the cogs into engagement with

the racks, and means for retarding the rotation of the cogs, substantially as set forth.

5. In a curtain-fixture, the combination of a spring-actuated curtain, a hollow curtain-stick, a sleeve in each end of said curtain-stick, each sleeve having a cylinder, a cog within each of said cylinders, a shoe carried by each sleeve having mounted therein a cog gearing with the cog within the cylinder, and

10 racks with which said last-named cogs engage, substantially as set forth.

6. In a curtain-fixture, the combination of a spring-actuated curtain, a hollow curtain-stick, a sleeve in each end of said curtain-

15 stick, each sleeve having a cylinder, a cog

within each of said cylinders, a shoe carried by each sleeve having mounted therein a cog

gearing with the cog within the cylinder,

20 racks with which said last-named cogs engage,

and means for outwardly thrusting the cyl-

inders and shoes carrying the cogs, substantially as set forth.

7. In a curtain-fixture, the combination of a spring-actuated curtain, a hollow curtain-stick, a sleeve in each end of said curtain- 25 stick, each sleeve having a cylinder, a cog within said cylinder, a shoe also carried by each sleeve having mounted therein a cog gearing with the cog within the cylinder, a rack with which each of said last-named cogs 30 engages, and rollers also carried by each shoe for bearing against the face of a rack, substantially as set forth.

In testimony whereof I hereunto set my hand.

PLATO G. EMERY.
